UNITED STATES PATENT OFFICE

IRVING W. FARQUHARSON, OF MEDIA, PENNSYLVANIA

DESIGN FOR A COMBINATION SCISSOR AND KNIFE SHARPENER

Application filed July 10, 1930. Serial No. 36,314. Term of patent 7 years.

To all whom it may concern:

Be it known that I, IRVING W. FARQUHARSON, a citizen of the United States, residing at Media, in the county of Delaware and State of Pennsylvania, have invented a new, original, and ornamental Design for a Combination Scissor and Knife Sharpener, of which the following is a specification, reference being had to the accompanying drawing, forming part thereof.

The figure is a perspective view of the article, showing my new design.

I claim:

The ornamental design for a combination scissor and knife sharpener as shown.

IRVING W. FARQUHARSON.
